UNITED STATES PATENT OFFICE.

EDITH M. GARLAND, OF ST. PAUL, MINNESOTA.

CUP HOLDER.

Application filed February 25, 1922. Serial No. 539,134.

To all whom it may concern:

Be it known that I, EDITH M. GARLAND, a citizen of the United States, residing at St. Paul, in the county of Ramsey and State of

5 Minnesota, have invented certain new and useful Improvements in Cup Holders, of which the following is a specification.

My invention consists of an improved holder for drinking receptacles, and is particularly designed for removably holding paper cups, its object being to provide a simple and cheap form of device for conveniently holding the ordinary paper cups, and improved means being provided where- 10
15 by the device may be collapsed to permit convenient packing away when not in use.

To this end my invention consists in the construction, combination and arrangement of parts hereinafter described and claimed.

20 Referring to the drawings:

Figure 1 is a side view of my device shown supporting a paper cup.

Fig. 2 is a plan view of the device collapsed.

25 Fig. 3 is a side elevation of Figure 2.

Figs. 4, 5 and 6 inclusive, are detail views illustrating a locking joint between the upper cup holding ring and side bars, and

30 Fig. 7 is a detail of the bottom of the device.

My improved holder, as shown, comprises a pair of side bars 2, formed at their upper ends with curved finger grips 3. Pivottally supported between the side bars by the pivots 4 and 5 is the upper ring 6 and the lower ring or bottom 7. The lower ring 7 is preferably formed with a solid bottom 8 to constitute a rest for the bottom of the cup 9.

To hold the rings 6 and 7 in collapsed position, the upper ring is formed with a projection 10, adapted to snap into a recess 11 in the side bar, and the lower ring is formed with a projection 12 adapted to snap into a recess 13 in the adjacent side bar.

45 When the holder is not in use the rings 6 and 7 may be turned into alinement with

the side bars as shown in Fig. 6 and held locked in this folded position by the projections 10 and 12 interlocking with the recesses 11 and 13. When thus folded the holder 50 may be conveniently packed away.

My improved holder is particularly adapted for picnic purposes, lunch kits, etc., where it is desirable to use paper cups and to save the work of carrying along and washing ordinary drinking vessels, the outwardly curved handles making it easy to handle the holder in passing it from one to another without the user's fingers coming in contact with the hot cup, where hot beverages are used. 55
60

By forming the lower ring with a solid bottom, a flat support for the cup is secured, and cups of different sizes may be used and held in the proper position within the 65 holder.

I do not restrict myself to forming the lower ring with a solid bottom. By providing locking means between the rings and side bars, I may in different ways modify 70 the construction within the scope of the invention as set forth in the following claims.

I claim:

1. A cup holder comprising side members one of which has a recess, a cup supporting ring between the members and pivotally connected to each for swinging therebetween to folded position, and a projection carried by the ring and engageable in the recess of said side member to secure the ring folded. 75
80

2. A cup holder comprising side members one of which has a recess, a cup supporting ring formed of a strip of metal and having overlapping ends, said ring pivotally mounted between the side members for folding therebetween, and one overlapping end having a projection interlocking with the recess when the ring is in folded position. 85

In testimony whereof I affix my signature.

EDITH M. GARLAND.
